(57) **CLAIM**

The ornamental design for a cable connector, as shown and described.

DESCRIPTION

FIG. 1 is a top plan view of a cable connector, showing my new design; the bottom plan view thereof is a mirror image thereto;

FIG. 2 is a side elevation view thereof; the opposite side elevation view thereof is a mirror image thereto;

FIG. 3 is a top and rear perspective view thereof; and,

FIG. 4 is a rear elevation view thereof.

The broken line showing of the environment is for illustrative purposes only and forms no part of the claimed design.
